UNITED STATES PATENT OFFICE.

JOHN E. SEDERHOLM, OF ST. PAUL, MINNESOTA, ASSIGNOR TO THE AMERICAN HOIST & DERRICK CO., A PARTNERSHIP COMPOSED OF F. J. JOHNSON AND W. O. WASHBURN, OF ST. PAUL, MINNESOTA.

CONTROLLER.

Application filed February 9, 1927. Serial No. 166,984.

This invention relates to improvements in motor controlling switch providing a primary or main line switch which operates instantaneously when manually operated, 5 along with a secondary switch, both switches being controlled by a single lever, and operable in a manner to cause a quick make and break of the primary switch, the circuit making movement of said primary switch 10 being made before the secondary switch closes its circuit.

An object is to provide an improved arrangement of contacts for a secondary switch element, in which contact fingers embrace the 15 members of rows of posts, during the resistance cut-out or cut-in operations, the fingers engaging in direction of the rows, and the corresponding members of the rows being aligned transversely to the direction of movement of the fingers to obtain a staggered arrangement.

Other objects of my invention are to eliminate or reduce the amount of arcing at 20 points of contact; to eliminate small screws in the contact path, which when used are frequently burned or welded over, and are very difficult to remove, when it is desired to renew the parts; to provide a primary or main line switch that operates instantaneously 25 when manually operated thus avoiding burning of the contacts; to provide a controller where all parts including the contacts are mounted on one panel thus making it possible to renew the entire contact mechanism or 30 any portion thereof very quickly; to simplify the general construction; to provide a compact arrangement of the elements.

Features of the invention include, all details of construction, as well as spatial relation 35 of the primary and secondary switch elements; the construction for rocking and reciprocating the switch elements, by means of a single pivoted lever, including also the manner of pivoting said lever, intermediate- 40 ly.

Advantages will be set forth in the description of the drawings forming a part of this application, and in said drawings:

Figure 1 is a front elevation with the box 45 cover removed and showing the parts in neutral or open circuit position;

Figure 2 is a view similar to Figure 1 showing the parts positioned, as when circuit is being made through the switch;

Figure 3 is a central vertical section on line 3—3 of Figure 1 showing how the parts are mounted on a single base in a manner to be quickly removed for replacement; 55

Figure 4 is a rear face view of the base or panel board 6;

Figure 5 is a plan section substantially on line 5—5 of Figure 1, showing construction of the reversing elements of the device; 60

Figure 6 is a fragmentary front face view showing the relations of the spring fingers to 65 the contact posts;

Figure 7 is a vertical section substantially on line 7—7 of Figure 3 illustrating the mounting of the spring fingers.

Figure 8 is a plan section on line 8—8 of 70 Figure 3 illustrating the mounting of the switch arms, with the arm in switch closed position; and

Figure 9 is a diagrammatic view illustrating a use of the device. 75

A rectangular casing is shown at 1 and is provided with front and rear covers respectively 2 and 3. Interiorly the casing is provided with vertically aligned top and bottom flanges respectively 4 and 5, bridging and attached to which is a base 6 of sheet insulating material. This base supports all the working parts of the apparatus, and the piece is removably secured as by bolts 7. 80

Upon the base a carrier or slide is translatably mounted. This mounting consists of a pair of spaced tracks or guides 10 suitably secured at opposite ends as by screws or bolts 11. These tracks are arranged in parallel relation and are adapted to support the carrier in this instance for vertical movement. The carrier is generally indicated at 15 and is provided with grooved vertical extensions 16 as slides, the grooves of which engage the guides 10 as best shown in Figure 7. Coiled 90 springs 20 are arranged beneath the carrier to urge the same upwardly in direction of spaced rows of contact posts 18, the carrier having fingers or contacts engageable with these posts in a manner to be described. 95

The arrangement and connection of the fingers upon the carrier are features of this invention. It will be noted that the fingers extend in direction of the reciprocation of the carriage 15 and that the fingers are spaced in a direction longitudinally of the carriage and transversely between the guides 10. The carriage 15 may be considered as a base, having 100 105

what may be considered raised abutments or projections 30, see Figure 7, flanked by extensions 31—32, the extensions 31 being aligned in direction lengthwise of the base or carrier 15. The extensions 31 are short, while the extension 32 is of a length substantially equal to that of the carrier. These plate-like extensions provide means for preventing lateral tipping of the fingers or arms, which are disposed in pairs and opposingly arranged one at each opposite side of the projection 30 as best shown in Figure 7 and have their edge surfaces slidably between the extensions. Means yieldably connecting each element directly above the projection are provided. Each means consists of a bolt 35 loosely traversing both arms. Surrounding the bolt is a coil spring 36 abutting one of the fingers 40 at the outer side, and at the other end abutting a stop formed by a washer 41 held against translation by a pin 42. The opposite end of the bolt is secured against translation by a pin 45 engaging at the outer side of the opposite finger. The elements 31—32 as before stated prevent lateral tipping, and act as guides between which the fingers are secured in upright position, with their outer terminal portions spaced. A pin 46 as means to prevent upward movement of the fingers is shown at 47 and said pin traverses the extensions 31—32. This pin lies directly above the pin or bolt 35 and in such a position as to prevent such upward movement of the fingers as would disengage the same from the projection 30. However, when the fingers are worn as a result for example of arcing any set can be quickly removed by removing the pin 46 and pulling upwardly. This construction provides a means whereby replacement can be easily and quickly made without dismantling any part of the apparatus with the exception of the disengagement of the pin 46. The fingers are assembled in pairs and when it is desired to place them, they are simply separated sufficiently to engage the projection 30 and allowed to spring back to frictional engagement at opposite sides of said projection or abutment.

In combination with the translatable carrier having the contact elements or fingers 40, a rockable switch arm is provided, which is adapted to be tipped by a lever 70, which is also associated through a link with the translatable carrier.

This rockable switch arm or device forms a feature of this invention and provides a knock-down construction composed of renewable parts, which can be quickly and easily attached or detached for purposes of assembly or replacement.

This device provides a pair of switch arms 49, see Figure 3, each independently rockably mounted and insulated. Standards 50, one for each arm are mounted in opposing relation and each of these standards has a pin 51,

said pins extending toward one another and being axially aligned. The pins are secured in this instance by threads and may be quickly removed. Each standard is secured to the insulating base by a bolt 52, and a bolt-like binding post, see Figure 8.

Each arm is medially bent as shown in Figures 5 and 8, the bend being in a direction away from the base 6, and lying substantially at the pivotal point of the arm. Upon that side 75 of the arm adjacent the base, one at each opposite end of the arm are knife blade projections 55 adapted respectively and alternately to engage contacts 56 secured by binding posts 57—58. Each arm has formed therein 80 at its outer side, one at each opposite end, a socket 60. The sockets of respective arms are aligned crosswise as best shown in Figures 1 and 2. These sockets are related substantially as the corners of a rectangle and within 85 the same insulating blocks 61 are removably socketed. A plate 62 connects the blocks as shown, and the plate is thus insulated by the blocks. This plate 62 is medially bent also in a direction away from the base and in the same degree as the arms, the object of this 90 bend being to provide means whereby when the end of the lever 20 engages at the bend portion both blades 55 will be disengaged from their contacts, thus disposing the switch arms in neutral position, in which neither 95 blade 55 engages a contact.

When it is desired to renew one of the switch arms 49, the plate and insulating blocks as a unit is lifted to disengage the 100 blocks 61 from the sockets, after which either arm can be translated inwardly to disengage the same from its pivot pin 51. Shields 65 are arranged substantially as shown.

A lever 70 is pivoted as at 71 on a bracket 105 72 and has its opposite arms respectively overlying the carrier and the rockable reversing switch device. As shown in Figure 1 the arrangement is such that when the lever occupies a midposition the contact fingers of the carrier and the blades of the switch arms 49 are all disengaged from their contacts. Moreover, the arrangement is such that the reversing switch is always brought to one contact position, before the carrier fingers engage any of their contacts. Moreover, the lever is arranged for translating the carrier in opposition directions when correspondingly swung, and the arrangement is such that when the lever is in mid-position 115 the carrier fingers are always disengaged from their contacts.

That arm of the lever 70 which overlies the reversing switch or rockable switch arm has translatable mounted therein a pin 73 125 having a button 76 frictionally engaging the plate 62, and slideable therewith to tip the arms or switch levers to opposite switch closed positions, when the lever is swung from the bend or midpoint of the element 62 in oppo- 130

site directions. A spring 75 engages the button to urge it in the direction of the plate 62. As a result of the swinging motion of the lever the rockable switch is alternately tipped 5 and forced to opposite switch closed positions, the reversing action taking place while the contact fingers 40 are disengaged from the terminal contact members 18. In this instance it is the short arm of the lever which 10 engages the plate 62.

The opposite or handle end of the lever is connected for translating the carrier. This connection comprises a slotted leverlike element 80 pivoted to swing, in this case, in 15 front of and adjacent the carrier. The element is adapted to swing generally in direction of reciprocation of the carrier and is connected to the carrier by a link 81, pivoted as at 82—83 respectively to the link and carrier, the connection with the carrier being substantially centrally thereof. The element 80 is provided with an irregularly shaped slot, and the lever is connected to the element 80 by means of a sleeve-like roller 85 rotatable upon 20 a stud 86 carried by the lever 70, see Figure 3. The roller rides in the slot to swing the slotted element and correspondingly translate the carrier. Thus the lever has one arm slidably connected with the slotted element. The opposite ends of the slot of the link form stops 25 to limit lever movement in opposite directions. The arrangement and configuration of the different portions of the slot is such that the contact fingers engage their contacts 30 whenever the lever is swung to opposite limits. As herein shown, the portions of the slot are arranged at angles to one another, both being curved. As the lever travels from its position shown in Figure 2, to the left the carrier 35 will be lowered, and when the roller reaches the point 90 the fingers 40 will all be disengaged from the contacts as shown in Figure 1. At this stage the lever is in its mid-position, and the reversing switch is open or in 40 neutral position. Upon continued movement 45 in the same direction through that portion of the slot designated 91, the link 80 will be raised to again assume substantially the same position as shown in Figure 2. This position of the lever 70 being shown in dotted lines at the left of the figure. In both positions of the lever indicated in Figure 2, the reversing switch is making contact.

The handle 95 of the lever 70 has a detent 50 engageable with notches 97 corresponding to the number of posts 18, in this instance, 9 on each side of the center line of the apparatus.

Another feature of the invention is the arrangement of the contact posts 18. These contact elements are arranged in rows, the members of each row being alined in direction of the reciprocation of the carrier. The members of the second row have a staggered 60 relation with those of the first, and the mem-

bers of the third row have a staggered relation to the members of the second row. The rows and the members of the rows are so related that the spring fingers successively engage the first member of respective rows in 70 sequence, the last pair of fingers engaging the first member of the last row before the first pair of fingers engage the second member of the first row, the action being continuous in this manner and in the same direction, 75 until the last pair of fingers engages the last member of the last row, at which time each finger is engaged with a contact. As shown in Figure 6 the first members of all rows are alined in a row extending transversely to the 80 direction of movement of the carrier. However, this row is not perpendicular to the path of the carrier, but forms an acute angle with a line which is perpendicular to the translative path of said carrier. The second 85 members of all rows are alined in a similar manner as are also the third members, the lines representing the alinement being substantially parallel. This arrangement provides the staggered relation above referred to.

The electrical connections are so made and the arrangement of the posts 18 is such, that at full speed position of the device shown in Figure 2, all resistances are cut out. This 95 is true for either full speed ahead or full speed reverse, the position of the lever 70 for these speeds being respectively shown in dotted and full lines in the figure.

It will be further noted that there are always four simultaneous contacts between the spring fingers, and the posts to keep the phases always closed.

The motor controller has herein been shown to be particularly designed for alternating current, and the device provides a quick make and break primary switch, while the secondary contact construction is much simplified. The present invention eliminates the use of leaf springs for contact fingers, 105 which are easily broken as the result of overstrain and crystallization. The present device also provides a control lever which has a swinging motion in a vertical plane, as distinguished from the old types of controller 110 which have a rotary motion, in a horizontal plane.

In Figure 9 the device is diagrammatically shown as connected to a three phase slip ring type of motor. The stator is indicated at 100 and the collector rings are respectively indicated 101, 102, 103. Main line wires are respectively indicated at A, B, C. The binding posts 57—58 are cross connected in pairs 120 respectively by connections 105—106. Connections from the binding posts 53 of the switch arm supports, are connected with the stator 100 respectively by wires 108—109 and the stator is additionally connected with the main line wire C by wire 110. Binding posts 125 130

58 are connected by wires 112—114 respectively with line wires B and A.

This completes the description for the motor connections with the reversing switch portion of the apparatus including the arms 49 of the primary switch. This switch is of the quick make and break type, this quick make and break feature being necessary in a controller where the circuit is broken thousands of time per day.

In Figure 9 the switch arms may be considered as in a position corresponding to forward rotation of the motor. In this position the arms 49 are in contact with their respective posts 57. In this position the current flows from line B through 112, 58, 105, 57, 49, 53, 109, 111, 108, 49, 56, 106, 58, 114 to line A.

After the primary switch has been closed as above described either for forward or reverse motor rotation, the secondary switch is then operated as a result of the continued swing of the lever 70 in the same direction. This lever has the detent 96 engageable in the notches 97, see Figure 1. The reversing switch is brought to contact position while the lever travels from the central notch, to the first notch, in either direction. During this movement, however, none of the fingers 40 (D—E—F of the diagram) come in contact with the posts 18, all of the induced current at this time passing through the resistance connecting bar 125, see upper right portion of Figure 9. In other words, all the resistance is still in circuit. During the movement of the detent from the first to the second notch, however, and by the time the detent has reached the second notch, fingers D and E have moved into contact respectively with posts 115, 116, that is into the first two members of the first or lower transverse row, cutting out the resistance between 134—135 and 133—132. The current then takes the following path: from collector ring 101, wire 138, to post 137, through resistance to post 135, through conductor 145, to post 115, through finger D, bar 15, finger E, post 116, conductor 146, to post 132, to post 130, to ring 102, thus completing the circuit for one phase.

In like manner, on continued movement of the carriage 15, fingers F engage post 117, and resistance between 126—127 is cut out, the post 117 being connected with 127 through wire 147. When fingers D engage post 118, of the second transverse row, this post being connected by wire 148 with point 136, resistance between 135—136 is cut out. When fingers E make contact with post 119 which is connected through wire 149 with point 131, resistance between points 132—131 is cut out. When fingers F make contact with post 120, which is connected by wire 150 with point 128, resistance 127—128 is cut out. When fingers D make contact with post 121, of the third transverse row which is connect-

ed by wire 151 with point 137, resistance between points 136—137 is cut out. When fingers E engage post 122, which is connected by wire 152 with point 130, resistance between points 131 and 130 is cut out, and finally when fingers F engage post 123, which is connected by wire 153 with point 129, resistance between 128 and 129 is cut out, and thus all resistance is out.

During reverse movement of the carrier 15 75 the resistances are cut in, in reverse order.

I claim as my invention:

1. A base, a carrier translatable thereon, having a contact element, a contact upon the base engageable by said contact element as 80 the carrier is translated, a lever having one arm connected for translating the carrier when swung, and a rockable switch arm adapted to be tipped alternately in opposite directions by the opposite arm of the lever 85 when the lever is correspondingly rocked.

2. A base, a carrier translatable thereon having a contact element, a contact upon the base engageable by said carrier contact element as the carrier is translated, a lever having one arm connected for translating the carrier in opposite direction when correspondingly swung, and a rockable switch arm adapted to be tipped by the opposite arm of the lever to opposite switch closed positions, 90 95 when the lever is swung, and passes from a mid-point in opposite directions.

3. A base, a carrier translatable thereon having a contact element, a contact upon the base engageable by the element as the carrier 100 is translated, a lever connected for translating the carrier in opposite directions when correspondingly rocked, a rockably mounted switch arm operable by the lever to be alternately rocked to switch contact positions, the 105 reversing action taking place while the contact finger is disengaged from the terminal contact.

4. A base, a translatable carrier thereon having a contact element, a series of terminal contacts upon the base successively engageable by the element as the carrier is translatable, a lever connected for translating the carrier when swung, and a rockable switch operable by the lever to be alternately tipped 115 and forced to opposite switch closed positions.

5. A base, a translatable carrier thereon having a contact element, a series of terminal contacts upon the base successively engageable by the element as the carrier is translatable, a lever connected for translating the carrier in opposite directions when correspondingly swung, a rockable reversing switch operable by frictional contact of the lever to be alternately rocked to reversing 125 switch contact positions, the reversing action taking place while the contact finger is disengaged from the terminal contact.

6. A base, a translatable carrier thereon having a contact element, a series of termi-

nal contacts upon the base successively engageable by the element as the carrier is translated, a lever connected for translating the carrier in opposite directions when correspondingly swung, a rockable reversing switch operable by the lever to be alternately forced to reversing switch contact positions, the reversing action taking place while the contact finger is disengaged from the terminal contact, and a spring urging the carrier in direction of the contacts, said lever being arranged and connected to force the carrier against the action of the spring, said connections being such that the contact element is disengaged from all contacts when the lever is at an intermediate point in its swinging arc.

7. An element rockably mounted as a reversing switch arm, having switch blades, contacts alternately engaged by said switch blades, a lever having an arm slidable against said rockable arm, said rockable arm being so configurated that when said lever assumes one mid-position both blades are disengaged from their contacts, and so that as the lever arm is swung in opposite directions the blades are correspondingly engaged with and disengaged from their contacts.

8. An insulating base, a carrier slidable thereon, a plurality of pairs of spring fingers mounted on said carrier, a plurality of rows of contacts, the members of each row alined in direction of the reciprocation of the carrier, the members being spaced for successive engagement by corresponding spring arms as the carrier is translated, the rows being so related that the spring fingers successively engage the first members of respective rows in sequence, the last pair of fingers engaging the first member of the last row before the first pair of fingers engage the second member of the first row, the action being continuous in this manner until the last pair of fingers engage the last member of the last row.

9. A device of the class described including an insulating base having a carrier translatable mounted thereon, a switch element upon the carrier, a contact engageable by the element as the carrier is translated, springs urging the carrier toward the contact, a slotted element pivoted to swing adjacent and connected to translate the carrier, generally in a direction of its translation, a rockable reversing switch arm having blades, contacts alternately engageable by said blades as the arm is rocked, the arrangement being such that both contacts are disengaged when the rockable element is in an intermediate position, a pivoted lever having one arm slidably connected with the slotted element and having its other arm slidable against the rockable switch arm, the arrangement being such that when the lever is at an intermediate position the rockable element is disengaged from both contacts and the carrier switch element is disengaged from its contact, the

arrangement further being such that the carrier is at the same translative limit, when the lever is at one of its limits of motion, the said link element forming a stop for the lever in opposite directions.

10. A device of the class described comprising a carrier translatable mounted, a switch element upon the carrier, a contact engageable by the element as the carrier is translated, a slotted element pivoted to swing generally in the direction of the carrier translation, and connected to translate the carrier, a rockable reversing switch arm having blades, contacts alternately engageable by said blades as the arm is rocked, a pivoted lever having one arm connected to ride in the slot of said slotted element, and having its other arm slidable against the rockable switch arm, the arrangement being such that the carrier is at the same translative limit when the lever is at either of its limits of motion.

11. A device of the class described comprising a carrier translatable mounted, a switch element upon the carrier, a contact engageable by the element as the carrier is translated, an element pivoted to swing and having a slot, said element connected to translate the carrier, a rockable switch arm, contacts alternately engageable by said arm as the switch is rocked, a pivoted lever having one arm connected to ride in the slot of the slotted element and having its other arm engaging the rockable switch arm, the arrangement being such that the carrier is at one translative limit when the lever is at one of its limits of motion, and the arrangement further being such that all switches are open when the lever assumes one intermediate position.

12. A device of the class described comprising a carrier translatable mounted, a switch element upon the carrier, a contact engageable by the element as the carrier is translated, an element pivoted to swing and having an irregular slot and connected to translate the carrier, a rockable switch arm having contacts alternately engageable by said switch blades, a pivoted lever having one arm connected to ride in the slot and swing the slotted element, and having its other arm arranged to reversibly rock the rockable arm, the arrangement being such that the carrier switch element is engaging its contact when the lever is at either of its limits of motion.

13. A device of the class described comprising, a base, a carrier slidable thereon and having a contact arm, a contact engageable by the arm when the carrier is translated, a slotted link pivoted to swing, a rockable switch arm having blades, contacts alternately engageable by said blades to close the circuit, a lever having one arm slidably connected in the slot of the slotted element

- and having its other arm frictionally engaging the rockable element to close the circuit through one contact when the lever occupies any but a mid-position, the connections between the slotted element and the lever being such that when in this mid-position the contact arm is disengaged from its contact, and the arrangement and configuration of the slot of said swinging element being such that the contact arm engages the contact when the lever is swung to opposite limits, said swinging element having a link connection with said carrier.
14. A base having a raised projection, fingers opposingly arranged one against each opposite side of said projection, means yieldably connecting said elements directly above the projection, means for preventing lateral tipping of the fingers or arms and a stop lying between the arms and above said yieldable connecting means to prevent upward movement thereof.
15. A device of the class described comprising a carrier slidably mounted having a contact finger, a contact engageable by the finger when the carrier is translated, a link pivoted to swing, a rockable arm having blades, contacts alternately engageable by said blades to close a plurality of circuits, a lever having one arm slidably connected to the swingable link and having its other arm slidable against the rockable elements to open both contacts when the lever occupies a mid-position, the connections being such that the carrier contact fingers only engage their contacts as the lever is swung to opposite limits from a mid-position, said swinging link element having a link connection with the carriage.
16. A base having a raised projection, fingers engaging against opposite sides of the projection, a bolt traversing the arms above the projection, a spring arranged on the bolt to force the fingers against the faces of the projections, and a pin lying above the bolt to prevent upward movement thereof.
17. A pair of arms each rockably mounted on a separate pivot, the pivots axially alined, and a plate having each opposite end connected with an insulating element, said insulating element removably socketed in said arms.
18. A pair of arms each rockably mounted on a separate pivot, said pivots axially alined in a direction transverse to the arms, each arm being only removable from its pivot in a direction toward the other arm, and each arm being bent intermediately in a direction away from its mounting, and a plate similarly bent and having its opposite ends connected with insulating element, said element being socketed in said arms.
19. A pair of arms independently rockably mounted, and a plate bent intermediately in a direction away from the mounting of the arms said plate having insulating elements 65 and said elements being detachably socketed in said arms.
20. A pair of switch arms, a mounting for each arm having a pivot upon which the arm is rockably supported and axially slidale for removal only in a direction toward the other arm and a plate having each opposite end connected to an insulating element, said elements being removably socketed in the arms to prevent sliding of the arms on their pivots, and to provide means by which the arms are rocked.
21. A base, a switch operating lever pivoted to the base, a switch arm arranged beneath one arm of the lever and rockably pivoted on an axis perpendicular to the pivotal axis of the lever, said lever arm having contact yieldably urged and slidale against the switch arm to rock the same in opposite directions as the lever is correspondingly 85 rocked, from a central position, a carrier translatably mounted for movement in the same direction as the pivotal axis of the rockable switch arm, and arranged beneath the other arm of the lever and having contact 90 fingers, contacts engageable by the fingers when the carrier is translated, means yieldably urging the carrier toward the contacts, a link having one end pivoted laterally of the carrier and arranged to swing between the 95 carrier and the last mentioned lever arm said link being angularly slotted and the slots being curved in opposite directions and meeting at a point medially of the link, means connecting the last mentioned lever arm, with 100 the link slot to swing the link and a second link connecting the slotted link to the carrier, the connections being such that when the lever is in a mid-position the carrier is in fully retracted position with its fingers disengaged from the contacts, and the rockable switch arm is in non-contacting position.
22. A pair of switch arms each independently rockably mounted and insulated and having a binding post, contacts for each arm also insulated and having binding posts and alternately engageable by corresponding arms, insulating blocks removably socketed in said arms at opposite sides of their pivots, and a plate connecting with and only engaging 115 said blocks said plate being medially bent in a direction away from the arms, and having the bend located substantially in the axis of rotation of the arms.
23. A base, a carrier translatable thereon 120 having a series of pairs of contact fingers, rows of spaced contact elements alined in direction of reciprocation of the carrier, members of the second row being staggered in relation to corresponding elements of the first, in a direction transversely to that of carriage reciprocation in such manner that the fingers of the second row engage the first 125

member of that row after the first finger has made contact with the first member of the first row and so successively throughout the contact movement of the carrier.

5 24. An insulating base, parallel rows of posts attached thereto perpendicularly, corresponding members of the rows being alined in direction transverse and at an angle to the direction of parallelism of the rows, a series 10 of contact fingers arranged for translation to successively contact the first members of the parallel rows when translated in direction of parallelism of the rows, the transverse alinement of the posts being such that the 15 fingers successively engage the first members of respective rows, such that the finger of the first row only engages the second post of the first row, after the last finger has engaged the first finger of the last row.

20 25. A device of the class described including a rockable switch element having contacts alternately engageable when rocked in corresponding directions, a second element translatable mounted and having contact 25 fingers, contacts engageable by said fingers as the element is translated, a lever having a link connection with the translatable element, and also having a sliding connection with the rockable element.

30 26. A device of the class described including a pivoted switch element having contacts alternately engageable when rocked in corresponding directions, a carriage translatable toward and away from the rockable 35 switch element in a direction parallel with its pivotal axis, and having contact fingers, contacts engageable by said fingers, and a lever arranged and connected to simul-

taneously rock the pivoted switch element and translate the carriage.

27. A device of the class described including a pivoted switch element having contacts alternately engageable when rocked in corresponding directions, a carriage translatable toward and away from the rockable 45 switch element in a direction parallel with its pivotal axis, and having contact fingers, contacts engageable by said fingers, and a lever arranged and connected to simultaneously rock the pivoted switch element and 50 translate the carriage, the arrangement being such that the pivoted element is rocked to a controlling position before the carriage contact fingers engage their contacts.

28. A pair of independently rockably 55 mounted switch arms, said arms only removable from their mountings in a direction toward one another, and an insulating element removably connected to the arms to prevent their disengagement from the mountings, 60 and an element connecting the blocks and extending in a direction lengthwise of the arms and at an angle to the rockable axes of the arms.

29. A base, a secondary switch comprising 65 a carrier translatable upon the base and having a contact element, a contact upon the base engageable by said element as the carrier is translated, a lever connected for translating the carrier when swung, and a rockable 70 primary switch adapted to be tipped by the lever when the lever is rocked.

In witness whereof, I have hereunto set my hand this 5th day of February, 1927.

JOHN E. SEDERHOLM.
